UNITED STATES PATENT OFFICE.

RICHARD E. BURGESS, OF KANSAS CITY, MISSOURI.

HYDROCARBON-VAPOR BURNER.

SPECIFICATION forming part of Letters Patent No. 773,192, dated October 25, 1904.

Application filed October 8, 1903. Serial No. 176,185. (No model.)

To all whom it may concern:

Be it known that I, RICHARD E. BURGESS, a citizen of the United States, residing at Kansas City, in the county of Jackson and State of Missouri, have invented certain new and useful Improvements in Hydrocarbon - Vapor Burners, of which the following is a specification.

My invention relates to improvements in hydrocarbon-vapor burners; and it consists in a generator for vaporizing water, a generator for vaporizing crude oil, and a burner wherein the water and oil vapors are thoroughly mixed to form a highly-combustible gas, which is ignited and consumed for the production of heat as it issues from said burner.

In order that the invention may be fully understood, reference will now be made to the accompanying drawings, in which—

Figure 1 shows a vertical sectional view of my improved device arranged in a heating-stove. Fig. 2 is an irregular transverse section of the same, taken on line II II of Fig. 1. Fig. 3 is a transverse section of the combination mixing-chamber and burner, taken on line III III of Fig. 1.

In the drawings I have shown my improved burner arranged in a stove 1 of ordinary or any preferred construction and provided at its lower portion with a register 2 for the admission of air, a collar 3 at its upper portion for connection with a chimney-pipe, and a grate 4 for the support of the burner, having a central rectangular aperture 5 for the reception of the rectangular lower end 6 of a screw-plug 7, having a conical upper end 8.

Plug 7 closes the lower end of a combination mixing-chamber and burner 9, provided at its upper portion with a series of inclined apertures 10 and at its lower end with a peripheral shoulder 11, against the under side of which is held an oil-pan 12 by peripheral shoulder 13 on the lower portion of plug 7.

The combination mixing - chamber and burner communicates at its upper end with a circular generator 14, through a connecting-nipple 15, and said generator is provided with an interior shoulder 16, surrounding the upper end of the nipple, to retain the oil in the generator until it becomes vaporized.

Oil is supplied to the generator through a valved supply-pipe 17, leading from an oil-tank. (Not shown.)

18 designates an annular generator suitably supported on the interior surface of the 55 stove-casing and surrounding generator 14. Generator 18 is larger than generator 14 in order to leave an intervening space 19, and it is provided with an annular chamber 20, arranged near its lower and inner surface and 60 divided by a transverse partition 21.

Generator 18 is semicircular in cross-section, its periphery being vertical to fit the vertical casing of the stove, while its semi-circular portion presents considerable surface 65 to the heat from the burner.

22 designates a supply-pipe leading from a water-tank (not shown) to chamber 20, with which it communicates near one side of partition 21. The flow of water through supply-pipe 22 is controlled by a cut-off valve 23, provided with an operating-handle 24 and a valve 25, which latter after being set to permit the passage of water only in such quantity as can be readily vaporized need not be further disturbed, as the cut-off valve 23 is alone manipulated to close or open communication between the water-tank and the generator. 75

As the water flows through chamber 20 to opposite side of partition 21 it becomes vaporized and escapes through a pipe 26, which extends down through the central portion of generator 14 and nipple 15 and terminates centrally above the apex of cone 8, which spreads the vapor, so it will thoroughly mix 85 with the vapor from generator 14.

In operation communication is opened between the oil-tank and the supply-pipe 17, which latter is also provided with valves 23 25, so the oil may flow into generator 14, from 90 whence it overflows into mixing-chamber 9 through nipple 15. It then flows from the mixing-chamber through apertures 10 into the oil-pan 12. After the latter has been filled to a proper depth the flow of oil through pipe 95 17 is shut off and the oil in the pan is ignited. The flame thus produced heats the mixing-chamber 9 and in passing upwardly between generators 14 18 impinges against the adjacent sides thereof, so the latter become highly 100

heated. The oil is then turned on and upon entering the heated generator 14 becomes vaporized and passes down into the mixing-chamber in the form of gas, which, issuing through 5 apertures 10, becomes ignited by the flame of the burning oil in pan 12. At the same time water is permitted to enter the annular generator 18, where in completing the circuit through chamber 20 it becomes vaporized and 10 in escaping through pipe 26 becomes superheated and is discharged against the apex of plug 7. As the vapor strikes the apex of the plug it is spread by the conical portion thereof and becomes thoroughly mixed with the vapor 15 from generator 14, producing a highly-combustible gas, which when ignited makes an intense heat unaccompanied by smoke or other objectionable products of combustion.

The several pieces forming the burner are 20 detachable, so new parts may be readily substituted when necessary.

From the above description it is apparent that I have produced a burner which is simple, durable, and cheap in construction and 25 thoroughly effective for the purpose intended.

Having thus described my invention, what I claim, and desire to secure by Letters Patent, is—

1. A hydrocarbon-vapor burner, having an 30 annular generator semicircular in cross-section and provided near its inner lower portion with an annular chamber, a transverse partition extending across said chamber, an inlet-pipe communicating with the chamber near 35 one side of the partition, an outlet-pipe communicating with the upper portion of the chamber near the opposite side of the partition, said outlet-pipe extending to the vertical axis of the generator where it descends and 40 terminates just above the lower edge of the generator, a circular generator arranged concentrically with the annular generator and of less diameter than the latter in order to leave an annular space for the passage of heat, an 45 inlet-pipe communicating with the upper side portion of the circular generator, an outlet-pipe communicating with the central bottom portion of the circular generator and surrounding the lower portion of the outlet-pipe 50 leading from the annular generator, and a

mixing-chamber and burner communicating with the lower end of the outlet-pipes of the generator, substantially as shown and described.

2. The combination with a stove having an 55 annular casing and grate-bar provided with a central opening, of a mixing-chamber and burner having a series of apertures in its upper portion and internal threads at its lower portion, a peripheral shoulder formed integral 60 with the lower end of said burner, a screw-plug engaging the threads of the burner and terminating at its upper end in a conical point, a reduced portion on the lower end of the screw-plug which engages the central opening 65 in the grate, a peripheral flange on the lower portion of the plug, an oil-pan clamped between the flanges of the burner and screw-plug, an annular-generator having a vertical 70 periphery to fit the interior surface of the stove-casing and provided with inlet and outlet pipes the latter terminating just above the conical point of the screw-plug within the mixing-chamber, and a circular generator having inlet and outlet pipes the latter communicating 75 with the upper portion of the mixing-chamber, substantially as shown and described.

3. A hydrocarbon-vapor burner, comprising 80 a mixing-chamber and burner, a circular generator located vertically above the burner, an inlet-pipe communicating with the upper side portion of the circular generator, an outlet-pipe connecting the lower central portion of the circular generator to the central top portion of the burner, an annular generator 85 encircling the circular generator a space being left between the two for the passage of heat, an inlet-pipe communicating with the annular generator, and an outlet-pipe extending from the upper portion of said generator to the 90 vertical axis thereof where it extends downwardly through the central portion of the circular generator and its outlet-pipe and terminates in the mixing-chamber.

In testimony whereof I affix my signature in 95 the presence of two witnesses.

RICHARD E. BURGESS.
